Z. E. Coffin,

Stop Cock,

No 64,198,

Patented Apr. 30, 1867.

Inventor:
Z. E. Coffin.

United States Patent Office.

Z. ERASTUS COFFIN, OF BOSTON, MASSACHUSETTS.

Letters Patent No. 64,198, dated April 30, 1867.

IMPROVEMENT IN STOP-COCKS.

The Schedule referred to in these Letters Patent and making part of the same.

TO ALL WHOM IT MAY CONCERN:

Be it known that I, Z. ERASTUS COFFIN, of Boston, in the county of Suffolk, and Newton, in the county of Middlesex, and State of Massachusetts, have invented certain new and useful Improvements in Stop-Cocks for water pipes; and I do hereby declare that the following is a full and exact description thereof, reference being had to the accompanying drawings, and to the letters of reference marked thereon. These drawings form a part of this specification.

Figure 1 is a sectional and internal view, one side being removed to show the valve and slides.

Figure 2 is also a sectional view taken transversely to the first, and also showing the edge view of the valve, a part of one slide or guide, J and C.

Figure 3 is a section at line A of the shell and line B of the valve.

Figure 4 shows the screws for operating the valve, with their connecting gears arranged for operating horizontally.

Like letters indicate the same or corresponding parts in all the figures or drawings.

a b c and d are the four separate parts of the shell or body of the cock. e is the valve, having the two faces, f, fitting, when the cock is closed, to the seats g. The valve, when the cock is open for the passage of water, &c., is drawn, as shown in figs. 1 and 2, into the chamber h. The valve e is furnished with bearings, i, on each side, to bear on slides or guides, J, for its guidance. These guides J are different from others used heretofore, in that they are made separately from the shell or body of the cock, and in one continuous piece, and afterward adjusted and fastened by screws or otherwise, within the shell or body, and not cast in or formed upon one or more sections of the shell. By this mode of construction the slides or guides are easily made and conveniently adjusted. The difficulty of planing up the slides within the shell is avoided, and an additional tie furnished for securing the several sections together. Also the liability of different sections of a guide made on the different sections of the cock to get out of line is avoided by this making of the slides separately and in one piece, and fastening them in. To effect the movement of the valve to and from its seats, it is furnished with two screws, k, arranged parallel to each other, and having their bearing in the shell or upon it. And the valve is furnished with nuts, l, for these screws to work in. This order, however, may be reversed, the screw being connected to the valve, and the nut to the shell and gears. The screws are connected together so as to operate simultaneously and equally by gears, as shown in fig. 1, or as shown in fig. 4, or otherwise, as by chain-wheels, band-wheels, &c. This insures the equal movement of the whole body of the valve, however much greater the friction or other resistance may be on one side than on the other. This is also particularly advantageous in the case of the taper valve, as it insures its seating properly and equally. When the bevel-gears are arranged as in fig. 4, the screws must be right and left-threaded, though the small bevel-wheels may both be arranged in the same relation to the large ones, in which case the screws may be threaded alike. In other particulars than those specified these stop-cocks do not differ materially, either in construction or materials, from such as are well known to the art.

Thus having described my improvements, what I claim as my invention, and desire to secure by Letters Patent, is as follows:

I am aware that the mere multiplication of parts is not my invention; but it will be perceived that whether my gate is pendent or horizontal, the steady direction of it in line with its guides cannot be secured by a single central screw, nor by several screws, except when operated by a system of gearing of simultaneous action. I therefore claim the taper valve operated by connected screws, and moving on continuous guides arranged within the shell or body of a stop-cock, substantially as described.

Z. E. COFFIN.
